CONTAINER AND POURING SPOUT

Henry Brucker, Maplewood, N. J.

Application October 11, 1934, Serial No. 747,818

3 Claims. (Cl. 221—11)

This invention relates to containers, or receptacles, for comminuted or granular substances, and more particularly to containers of the class having a discharge aperture and a pouring spout

5 connected to the container for swinging movement to close the aperture or to open the same so that the contents of the container may be poured therefrom through said aperture and spout.

10 One object of my present invention is to provide a container and spout embodying improved features of construction and a novel relation whereby the discharge aperture in the container may be more effectively sealed than with devices 15 with which containers of this class are commonly equipped.

Another object is to provide a container having a discharge aperture and a tab cut therefrom to hingedly support the spout and completely 20 formed during manufacture of the container so that it is normally free to be swung outwardly for application of the spout thereto from the outside of the container whereby said spout and container may be easily and quickly assembled.

25 Another object is to provide an improved and novel relation of tab and spout whereby they act conjointly to effectively seal the discharge aperture and are securely held in sealing position against accidental displacement as during packing and shipping.

30 Other objects are to provide a container and spout of the character described which are simple in construction, strong and durable, and economical to manufacture; and to obtain other advantages and results as will appear when the following description and claims are read in conjunction with the accompanying drawing.

35 In the drawing wherein like parts are designated throughout the several views by corresponding reference characters:

40 Figure 1 is a fragmentary view in vertical transverse section of a container and spout constructed according to my invention and showing the spout applied to the container cover and in normal closed position.

45 Figure 2 is a similar view showing the spout in its discharge or open position and the container and spout tilted for pouring the contents of it therefrom.

50 Figure 3 is a fragmentary view in top plan of the container cover with the spout in closed position.

55 Figure 4 is a similar view of the container cover before the spout is applied thereto.

Figure 5 is a fragmentary view in bottom plan

of the container cover with the spout applied thereto.

Figure 6 is a view in transverse section taken on the line 6—6 of Figure 3.

Figure 7 is a similar view taken on the line 7—7 of Figure 2, and

Figure 8 is a perspective view of the spout.

Specifically describing the illustrated embodiment of my invention, the reference character 1 designates a container comprising a body portion 2 and a cap member 3 forming an end wall 4. The container 1 may be formed of any suitable material such as card board, fiber board, or the like. One wall of said container, preferably the end wall 4, is provided with a substantially rectangular discharge aperture 5 and a correspondingly shaped tab 6 integrally connected to said wall at one end of said aperture for hinging movement into and out of the latter and for a purpose presently clear.

Cooperating with the container 1 is a pouring spout 7 adapted to close the aperture 5 and secured to said tab 6 for movement to opening and closing positions. The spout 7 is preferably formed of thin sheet metal bent upon itself to provide a flat body portion 8 and sector shaped side walls 9 at the side edges of said body portion and having arcuate outer edges 10 concentric with the axis of movement of the tab 6. Said spout is of the same width as the aperture 5 so as to frictionally engage the outer faces of the side walls with the side edges of said aperture 5, and the body portion 8 is longer than said tab 6 to provide an extension 11 projecting beyond the free end of said tab 6 for a purpose to be explained. A pair of prongs 12 is shown on the body portion 8 for securing the spout to the tab 6, but more prongs may be provided if desired. At least one prong is disposed adjacent the hinged end of the tab 6.

In applying the spout 7, side walls 9 of the spout are slipped through the slots between the sides of the aperture and the edges of the tab 6, and the spout is then placed over the tab with the body portion 8 overlying the outer face thereof and the side walls 9 engaging the side edges of the aperture 5. The body portion 8 is then secured to said tab 6 by forcing the prongs 12 through the tab and clinching them, as shown in Figures 2, 5, and 7, to positively connect the tab 6 and body portion together and prevent relative movement or displacement thereof. When the tab 6 and spout 7 are swung inwardly until said body portion 8 lies flat against the wall 4, the aperture 5 is closed, the side walls 9 seal the side

edges thereof by friction, and the extension 11 engages said wall to seal the corresponding end of said aperture and also serves as a stop limiting further movement of said spout in a closing direction.

A particular feature of my invention is a fixed tongue 13 at the free end of the aperture 5, formed by an extension of said wall 4, the free end of which is adapted to be frictionally engaged by the free end of the tab 6 in closing position of the spout 7 to hold the latter in said position and to also form an additional seal at the free end of said aperture. As shown in Figure 5, the tongue 13 extends between the side walls 9 of the spout 7 and the side edges of the tongue engage said walls to hold them apart and in frictional engagement with the side edges of the aperture 5.

To additionally seal the aperture 5, and as shown in Figure 5, the tab 6 is imperforate and fits flush against the inner face of the body portion 8 of the spout 7 and also against the inner faces of the side walls 9 of said spout to thereby form a seal between the tab and spout and retard entrance or exit of air or moisture into or from the container between said tab and the spout.

When it is desired to open the aperture to pour the contents of the container through the spout 7, the latter is moved to open position by grasping the extension 11 and swinging the tab 6 and spout outwardly. To limit such outward movement, lugs 14 are provided on the side members 9 for engagement with the inner face of the wall 4. If desired a protecting piece of paper 15 may be pasted to the wall 4 to cover said spout 7 in its closed position although this is not essential to my invention.

With the described construction and relation of container and spout, the aperture 5 is completely sealed around its edges and double sealed at the vital point, i. e. its free end, as will be clear. This is particularly advantageous in a container designed for use with goods such as coffee, tea, or spices, which as is well known deteriorate when exposed to atmospheric air for any length of time. As will be manifest the tongue 13 and tab 6 form in effect a friction lock for the spout 7 which together with the aperture 5 and tab 6 may be stamped or cut out of the wall 4 in one operation and whereby the carton 50 may be economically manufactured. By completely forming the aperture 5, tab 6 and tongue 13 in the manner described, they may be provided with clean cut straight edges nicely fitting the side walls 9 of the spout 7 and forming a tight fit between said tab and tongue.

While I have shown and described my invention as embodied in certain specific details of construction and relations of parts it is to be understood that the present disclosure is primarily illustrative of the principles of the invention and that modifications in details of construction may be made without departing from the spirit or scope of the invention.

Having thus described my invention, what I claim is:

1. The combination with a container having a substantially rectangular discharge aperture in one wall thereof, of a tab hingedly connected to said wall at one end of the aperture for swinging movement into and out of said aperture, and a pouring spout secured to said tab for movement therewith to open and close said aperture and comprising a body portion overlying said tab and provided with an extension adapted to project beyond the free end of said tab and the other end of said aperture for engagement with said wall in the closed position of the spout to limit closing movement of the spout and to seal said outer end of said aperture, and sector shaped side walls on said body portion having their outer faces frictionally engaging the side edges of said aperture to seal said edges in the closed position of said spout, said tab being imperforate and fitting flush against the inner face of the body portion of said spout and also against the inner faces of the side walls to form a seal between said tab and spout, and the free end of said tab frictionally engaging said wall to hold the spout in closed position.

2. The combination with a container having a substantially rectangular discharge aperture in one wall thereof, of a tab hingedly connected at one end of the aperture to said wall for swinging movement into and out of said aperture, and a pouring spout secured to said tab for movement therewith to open and close said aperture and comprising a body portion overlying said tab and provided with an extension adapted to project beyond the free end of said tab and the other end of the aperture for engagement with said wall in the closed position of said spout to limit closing movement of the spout and to seal said other end of the aperture, and sector shaped side walls on said body portion frictionally engaging the side edges of the aperture, and a tongue extending from said other end of said aperture between said walls for holding said walls in frictional engagement with the side edges of the aperture, the free end of the tab frictionally engaging said tongue in the closed position of the spout to hold the latter in said position and seal the aperture.

3. A container having formed in one wall thereof a substantially rectangular aperture, and a tab integrally connected at one end to said wall for hinging movement into and out of said aperture, the wall of the container forming a short tongue at the opposite end of said aperture in the plane thereof having a free end adapted to be frictionally engaged by the free end of said tab to hold said tongue in said aperture, the side edges of said tab and tongue being slightly spaced from the side edges of said aperture to frictionally receive portions of a pouring spout.

HENRY BRUCKER.
